FIG. 1

FIG. 2

FIG. 4

FIG. 3

FIG. 5

FIG. 6

FIG. 7

FIG. 1 is a perspective view showing the new design for a check valve,

FIG. 2 is an elevational view of this check valve,

FIG. 3 is a perspective view from the opposite side shown in FIG. 1,

FIG. 4 is an elevational view from the opposite side shown in FIG. 2,

FIG. 5 is a cross-sectional view taken on the line 5—5 of FIG. 2 and showing the relative position of a pipe structure in light line for illustration purposes only,

FIG. 6 is a cross-sectional view similar to FIG. 4 but showing a modification of the yoke portion of the valve, and

FIG. 7 is a modified form of the check valve shown in

FIG. 1, the differences residing in the specific configuration of the central portion of the valve body.

The broken lines are shown for illustrative purposes only.

I claim:

The ornamental design for a check valve, as shown and described.
